LOCOMOTIVE FIREBOX EQUIPMENT

Chester A. Siegel, Newark, N. J., assignor to
American Arch Company, New York, N. Y., a
corporation of Delaware

Application December 20, 1941, Serial No. 423,845

10 Claims.

(Cl. 122—68)

This invention relates to locomotive firebox circulation equipment, the invention being particularly applicable in a firebox having water walls at the throat, sides and rear, and a water space above the crown. Many features of the invention are also related to support of a fire brick arch.

One of the principal objects of the invention is the provision of water circulation means having a multiplicity of inlet and outlet connections adapted to effect circulation of water from a plurality of the generally upright water wells surrounding the box to the boiler space above the crown sheet.

In accordance with another feature of the invention the total circulation flow is divided between several circulator devices, each of which preferably has two or more outlet connections, all of the outlet connections being extended to the crown sheet and distributed over a substantial area thereof, whereby to afford effective flow over the crown sheet without the necessity of cutting large openings in the crown sheet, such as the elongated apertures required by certain prior types of circulators. In this way weakening of the crown sheet is avoided, while yet providing widely distributed outlet flow to the crown sheet.

The invention also contemplates employment of circulator devices which support arches generally longitudinally of the firebox, and which have forward and rearward inlet legs rising to a point of junction, from which junction outlet means common to the two inlet legs rises generally vertically directly to the crown sheet. This general configuration of circulator device has several important advantages, one of which is the provision of simple and effective arch brick support, another of which is bracing of the crown sheet, and a third of which is improvement of water circulation as a result of the two-fold inlet providing for intake of water from widely separated points in the upright water walls surrounding the firebox.

Another point of advantage of the invention is the provision of circulator devices having upwardly and rearwardly inclined inlet legs in spaced side-by-side relation to support a fire brick arch, together with additional circulator devices constructed for installation above said arch and providing multiple outlets in the crown sheet in the region above the arch.

A further object of the invention may be generally defined as simplification of manufacture and installation of the circulator devices. In achieving this end, the invention contemplates employ-

ment of a "junction" unit which is adaptable to circulators of different types, located in different positions in the firebox. More specifically, this junction unit comprises, in the preferred form, an adapter element having a pair of outlet legs and a pair of inlet legs all interconnected in a common junction, the outlet legs being extended generally parallel to each other and being of length such as to extend to the crown sheet from any of a plurality of positions in which a circulator is to be installed in the firebox. The inlet legs, on the other hand, are preferably relatively short and arranged to extend from the common junction generally in opposite directions but in the plane of the outlet legs, whereby said inlet legs may be coupled through tubing, alternatively, with the throat sheet and/or one or more of the other generally upright water walls surrounding the firebox. In this way a single unit or adapter may be used to constitute a major portion of any one of several different circulator installations.

The foregoing and other objects and advantages will appear more fully from the following description referring to the accompanying drawings, in which—

Figure 1 is a longitudinal vertical sectional view taken through a locomotive firebox equipped with circulator devices in accordance with the present invention.

Figure 2 is a plan view of the circulators and fire arch of the form of Figure 1, the side sheets of the firebox being shown in horizontal section approximately as indicated by the line 2—2 on Figure 1;

Figures 3 and 4 are views corresponding to Figures 1 and 2 but illustrating a modified arrangement, the side sheets in Figure 4 being shown in horizontal section as indicated by the line 4—4 on Figure 3;

Figure 5 is a longitudinal vertical sectional view through a locomotive firebox equipped with another arrangement of circulator devices in accordance with the invention;

Figure 6 is a transverse sectional view taken substantially as indicated by the line 6—6 on Figure 5; and

Figures 7 and 8 are views corresponding to Figures 5 and 6 but illustrating still another modified arrangement, Figure 8 being taken as indicated by the line 8—8 on Figure 7.

Throughout all of the views the same reference characters are used to designate various of the walls defining the firebox, as follows:

9—9 The side sheets are indicated at 9—9, and the

crown sheet at 10, these sheets 9 and 10 cooperating with a wrapper sheet 11 to form water walls at the sides of the firebox and a water and steam space above the crown sheet.

At the backhead, inside and outside sheets 12 and 13 cooperate to form a water wall in communication with the side water walls and with the space above the crown sheet, the backhead being provided with a fire door 14.

At the throat, inside and outside sheets 15 and 16 serve to define a water space also in communication with other water walls surrounding the firebox.

The flue sheet 17 is disposed toward the forward end of the firebox or a secondary combustion chamber extended forwardly from the firebox proper. Flue tubes 18 communicate with the firebox and extend forwardly through the boiler barrel.

A mud ring 19 serves to close the lower edges 20 of the water walls at all sides of the firebox.

In the arrangement of Figures 1 and 2, five circulators are employed, two of which, constituting a pair, are indicated generally at 20-21. Two more of the circulators are arranged as another pair, being indicated generally at 22-23. The fifth circulator is designated 24.

Circulators 20 and 21 are similar, each comprising a pair of inlet legs 25-26, the former extending forwardly and downwardly for connection with the boiler space at the throat sheet 15, and the latter extending downwardly and laterally for connection with side sheets at opposite sides of the firebox.

Inlet legs 25 and 26 are connected with the junction unit 27 having a pair of inlet connections 28-29 (for cooperation with inlet legs 25 and 26), and further having a pair of outlet connections 30-31 adapted to be directly connected with the boiler space through the crown sheet 10. As clearly appears in Figure 1, the junction unit 27 provides a common junction between the two inlet legs and the two outlet legs of the circulator considered as a whole. It will also be noted that inlet connections 28-29 extend generally in opposite directions from the point of junction, while outlet connections or legs 30 and 31 extend from the junction in generally parallel relation, all of the connections lying substantially in a common plane.

The junction unit just described is constructed in the manner indicated in order that this same unit may alternatively be employed for a circulator of the type shown in Figures 1 and 2, or for circulators of other types described herein-after. By making this circulator unit adaptable to various circulator arrangements, maximum convenience and economy are afforded in applying the circulator installations to locomotives of different types.

The junction unit may be fabricated in various ways, as by bending flat sheet blanks to form half-pieces, and then welding a pair of such pieces together at edges abutting each other in the mean plane of the unit considered as a whole. The inlet connections of the unit may then be welded to appropriate leg tubing, for instance seamless tubing, thereby providing a simple and durable circulator construction.

In the arrangement of Figures 1 and 2, the water circulation system further includes the additional pair of circulators (22-23) hereinbefore mentioned, the elements of this pair being similar to each other. Although each of these circulators may, if desired, be constructed as a sin-

gle integral unit, in the preferred arrangement, each comprises a primary body section 32 having an inlet connection 33 and a plurality of outlet connections 34 and 35, all of which connections 5 are adapted to cooperate with tubular inlet and outlet legs 36, 37 and 38. The inlet leg 36 extends downwardly and laterally to one of the side sheets 9, as clearly appears in Figure 2; and outlet legs 37 and 38 all project upwardly for communication with the boiler space above the crown sheet 10.

With respect to circulators 22 and 23, it is to be noted that each provides for circulation from a side sheet to the crown sheet, the delivery to the crown sheet being divided among a plurality of outlet legs which are spaced from one another over a substantial length of the crown sheet. In this way provision is made for wide distribution of circulation to the crown sheet without necessitating formation of a large elongated slot in the crown sheet, such as has been required with certain prior types of circulators. The somewhat flattened body portion 32 of each of these circulators also is of advantage for high heat absorption. The relatively large volume of water in the body portion 32 serves as a reservoir from which the outlet legs draw. Since the body portion 32 serves as a common junction for all of the inlet and outlet legs of each circulator (22 or 23) uniformity of distribution as between the outlet legs is provided.

As shown in Figure 2, arch bricks 39 are supported between the inlet legs 25 of circulators 20 and 21 and also between said inlet legs and the side sheets. Because of the location of the junction units 27 well rearwardly in the firebox, the long inlet legs 25 extending in parallelism forwardly to the throat sheet are ideally suited to the support of an unbroken fire brick arch, which arch, moreover, requires few, if any, different brick shapes.

It is further pointed out that an unusually simple arch brick installation is provided, notwithstanding the fact that a multiplicity of circulators is employed in the firebox, having extensive heat absorption surfaces. The extensive surface area of the circulators 22 and 23 is particularly advantageous in utilizing the heat of the flame and gas stream in the region of the firebox above the arch.

If desired, further utilization of the heat of the flame and gas stream may be effected by the circulator 24 which is disposed in the forward extension of the combustion chamber, as clearly appears in Figure 1. This circulator 24, generally in the form of an inverted Y, comprises a transversely extending and upwardly arched inlet portion 40, opposite ends of which are connected with the water space of the boiler at opposite sides of the combustion chamber, together with an outlet leg 41 connected with the inlet portion in the central region thereof and extended upwardly for delivery of water to the space above the crown sheet 10.

Use of a circular such as that just described cooperates with the other circulator devices in providing wide distribution in the delivery of water to the crown sheet.

The circulation system considered as a whole is highly effective in providing active circulation from many different points at the sides of the firebox, to the space above the crown sheet.

In the modification of Figures 3 and 4 a pair of circulator devices 20a and 21a are employed, these being essentially similar in arrangement and con-

struction to the devices 20 and 21 described above in connection with Figures 1 and 2. In Figure 4, moreover, a circulator 42 is also employed, this unit being similar to circulators 22 and 23 of the first form. Here, however, this circulator is disposed between circulators 20a and 21a, and the body portion 32a thereof has an inlet neck or leg 43 connected with the throat sheet, which is in contrast with Figures 1 and 2, wherein the inlets for circulators 22 and 23 are coupled with the side sheets. The outlet connections 34a of body 32a are adapted to be coupled by legs 31a with the space above the crown sheet. The flat body part 32a of circulator 42 would ordinarily be stay-bolted for strength.

As seen in Figure 4, circulator 42 is provided with ledges or bulges 44 extending along the lower edge of the body 32a in parallelism with inlet legs 25 of the circulators 20a and 21a in order to cooperate therewith in providing for support of arch brick 45 (see Figure 3). It will be understood that additional arch brick will be carried between the inlet legs 25 and the side sheets, as in Figures 1 and 2, so as to complete the fire arch.

The firebox of Figures 3 and 4 is considerably shorter than that illustrated in Figures 1 and 2, and the several outlet connections 37a of circulator 42 are uniformly spaced lengthwise of the crown sheet substantially throughout the length thereof, thereby providing effective delivery and distribution of water over substantially the entire area of the crown sheet. Outlet connections 30 and 31 of circulators 20a and 21a further enhance the delivery and distribution of water to the crown sheet.

From the foregoing it will be seen that the two principal types of circulators already discussed are adaptable to fireboxes of various sizes and shapes. Note also that circulators 20a and 21a each includes the junction unit 27.

In Figures 5 and 6 still another arrangement is illustrated, this installation again including a pair of circulators 20b and 21b, essentially similar to circulators 20 and 21 described above.

However, instead of providing for wide distribution of flow to the crown sheet in the manner of Figures 1 to 4, the arrangement of Figures 5 and 6 achieves this end by the employment of a series of "cross" circulators, indicated generally at 46, 47, 48 and 49. Each of these units incorporates a junction unit 27 the same as that employed in circulators 20, 21, 20a, 21a, 20b and 21b. In the instant arrangement, however, each unit 27 is disposed in a transverse vertical plane instead of in a longitudinal vertical plane, the outlet legs 30 and 31 being connected with the crown sheet, and the inlet connections 28 and 29 being coupled through legs 50-50 with the side sheets 9-9. For the purpose of assuring maximum gas contact with the surfaces of circulators 46 to 49, the inlet connections 50-50 for these several units are preferably located at different elevations, as clearly appears in Figure 5. In adapting the junction unit 27 to each of these units, it is only necessary to cut off more or less of the outlet legs 30-31. Although the fire brick are not shown in Figures 5 and 6, it is to be understood that a fire brick arch is adapted to be supported between the inlet legs 25 of circulators 20b and 21b and between said inlet legs and the side sheets, as in Figures 1 and 2.

Figures 5 and 6 further illustrate the adaptability of applicant's junction unit 27 to meet the requirements of different circulator and firebox installations. As in Figures 1 to 4, provision is

again made for effective delivery and distribution of water to the crown sheet and for circulation of water from various of the side sheets at widely separated points, to the crown sheet.

The advantages just mentioned with regard to circulation are also achieved by the arrangement of Figures 7 and 8 in which there is again employed a pair of circulators 20c-21c. Here also the arch bricks 39 are supported on the elongated inlet legs 25 of these circulators.

In the form of Figures 7 and 8, however, the additional circulation to the crown sheet in the region above the arch is provided by a circulator 51 having transversely extended inlet legs 52-52 connected with the side sheets and further having a body portion 53 with a plurality of outlets 54 connected with the crown sheet. The body portion 53 provides a common junction between all of the inlet and outlet legs, and this body portion preferably has sufficient volume to serve as a reservoir from which the outlet legs may draw, so as to enhance uniformity of delivery of water to the crown sheet over a substantial area thereof. Although the inlet legs 52 of circulator 51 are extended transversely for connection with the side sheets, the outlet legs, as clearly appears in Figure 7, are spaced from each other lengthwise of the crown sheet. Outlet connections 54 cooperate with outlet connections 30-31 of circulators 20c and 21c in providing for circulation to the crown sheet at a multiplicity of spaced points.

It will be observed that all of the modifications have a number of advantages in common, including that mentioned just above (effective and wide distribution of the circulation over the crown sheet), and also circulation of water from many different points at the upright walls of the firebox to the crown sheet. All of the arrangements are further of advantage in providing an unusually simple and effective arch brick support, notwithstanding the employment of a multiplicity of circulator devices having extensive total surface area exposed for heat absorption from the flame and gas stream.

From the drawings and description it is apparent that applicant's principal types of circulators are highly adaptable to meet the conditions of different fireboxes. Moreover, it will now be seen that applicant has made provision for utilization of a single junction element in a variety of types of circulators meeting the requirements of different installations.

I claim:

1. In a locomotive firebox having a throat sheet, a crown sheet and upright sheets at the sides and backhead, a plurality of generally longitudinally extending water circulator devices each interconnecting the throat sheet, the crown sheet and one of said upright sheets, the legs of said devices which are connected with the throat sheet being extended upwardly and rearwardly therefrom in spaced parallel relation, arch brick supported on said legs to form a fire arch lying in a plane inclined upwardly and rearwardly from the throat sheet, and another separate circulator device in the firebox above the fire arch interconnecting an upright side sheet and the crown sheet.

2. A construction in accordance with claim 1 in which a plurality of said separate circulator devices above the fire arch are provided, one interconnecting one upright side sheet and the crown sheet and the other interconnecting the other upright side sheet and the crown sheet.

3. A construction in accordance with claim 1 in which a plurality of said separate circulator devices above the fire arch are provided, one interconnecting one upright side sheet and the crown sheet and the other interconnecting the other upright side sheet and the crown sheet, and each having a plurality of outlets in the crown sheet.

4. A construction in accordance with claim 1 in which said separate circulator device has an inlet leg connected to each of the opposite side sheets and an outlet connected with the crown sheet.

5. A locomotive firebox having a throat sheet, a crown sheet, and upright sheets at the side and back head, a circulator device having an inlet leg connected with the throat sheet and extending upwardly and rearwardly, a second inlet leg connected with one of said upright sheets at the rear end of the firebox and extending upwardly and forwardly, and a common junction member, said inlet legs being connected to opposite sides of said member at the lowest part thereof and the upper part of said member being connected to the crown sheet.

6. A construction in accordance with claim 5 in which said second inlet leg is connected with a side sheet.

7. A construction in accordance with claim 5 in which the junction member has a plurality of connections with the crown sheet.

8. A construction in accordance with claim 5 in which the junction member has a plurality of connections with the crown sheet, said connections being spaced longitudinally of the firebox.

9. A locomotive firebox having a throat sheet, a crown sheet, and upright sheets at the side and back head, a plurality of circulator devices each having an inlet leg connected with the throat sheet and extending upwardly and rearwardly, and a second inlet leg connected with one of said upright sheets at the rear end of the firebox and extending upwardly and forwardly, and a common junction member for each circulator device, the inlet legs of each circulator being connected to opposite sides of said member at the lowest part thereof and the upper part of said member being connected to the crown sheet, the said first mentioned inlet legs being substantially parallel but spaced from each other and arch brick supported on these inlet legs to define a fire arch lying substantially in a plane inclined upwardly and rearwardly from the throat sheet.

10. For a locomotive firebox having a throat sheet, a crown sheet, and upright sheets at the side and back head, a plurality of circulator devices one of which has an inlet leg connected with the throat sheet and extending upwardly and rearwardly, a second inlet leg connected with one of said upright sheets at the rear end of the firebox and extending upwardly and forwardly, and a common junction member, said inlet legs being connected to opposite sides of said member at the lowest part thereof and the upper part of said member being connected to the crown sheet, and another of said circulator devices having an inlet leg connected with the boiler space at the forward end of the firebox and a plurality of outlet legs connected with the crown sheet.

CHESTER A. SIEGEL.
